UNITED STATES PATENT OFFICE.

ANNE VOETBERG, OF RACINE, WISCONSIN.

PERPETUAL CALENDAR.

1,376,981.

Specification of Letters Patent. Patented May 3, 1921.

Application filed February 24, 1920. Serial No. 360,684.

To all whom it may concern:

Be it known that I, ANNE VOETBERG, a subject of the Queen of Holland, and resident of Racine, in the county of Racine and State of Wisconsin, have invented certain new and useful Improvements in Perpetual Calendars; and I do hereby declare that the following is a full, clear, and exact description thereof.

10 My invention pertains to new and useful improvements in calendars, particularly of that type which are changed day by day to display the proper date.

15 The primary object of the invention is to provide a simply constructed device of this nature in which the date characters are effectively arranged in alinement and in association with advertising matter or the like which forms a part of the complete article.

20 A further object of this invention is to provide a novel means for rotatably supporting the disks or similar members which carry the date characters. By the use of such an arrangement my device may be constructed 25 comparatively inexpensively and thus can be marketed at a slight cost.

With these general objects in view the invention resides in the novel features of construction, combination and arrangement of 30 parts which will be hereinafter more particularly described and claimed and shown in the accompanying drawing wherein:

Figure 1 represents a front elevational view of a calendar constructed in accordance 35 with the invention.

Fig. 2 is a horizontal sectional view on the plane of the line 2—2 of Fig. 1.

Fig. 3 is a fragmentary rear elevational view showing particularly the means for rotatably supporting one of the date character 40 disks.

Fig. 4 is a detail transverse sectional view through a calendar showing a modified means for rotatably mounting one of said 45 date character disks, and

Fig. 5 is a plan view of one of said disks.

In the present showing of the invention I have illustrated my improved date display means associated with a frame carrying a 50 mirror. This may be plain or contain suitable legends of an advertising nature, or the mirror may be omitted and the portion of the device occupied thereby provided with advertising matter or the like. Various 55 other changes may be made in the calendar device and in the manner of assembling the

various parts thereof without departing from or sacrificing any of the principles of the invention.

Referring now more particularly to the several figures of the drawing, it will be noticed that the numeral 1 denotes a front or face plate of a suitable size and shape having its upper portion provided with an opening 2 through which said mirror 3 is visible, 65 while the reference character 4 designates a backing plate of the same size and shape as the plate 1, both of which plates are mounted within a suitable frame 5. The two plates 1 and 4 are spaced apart the thickness of the 70 mirror 3 by means of spacing strips 6 or the like.

Below the mirror 3 I preferably locate my improved date display means. In the present instance I display the date of the week, 75 the day of the month, the month of the year, and the number of the year in horizontal alinement across the face plate 1 between the lower edge of the opening 2 and the bottom 80 of the frame 5. The characters or symbols 85 representing such dates are visible through a series of openings 7 cut in the face plate 1 and arranged in a horizontal row.

The necessary symbols are printed or otherwise fashioned on a series of disks 8, 85 one of which disks is adapted to be located behind each of the openings 7 and between the face plate 1 and backing plate 4. Inasmuch as certain of the disks necessarily 90 contain more symbols than the others said disks are of dissimilar sizes and are therefore not arranged in alinement as are the openings 7. The backing plate 4 is provided with a series of circular openings 9, one 95 of which is alined with the center of each disk 8. Through these openings 9 the disks may be revolved to bring the proper date symbol in registration with the openings 7, and the means for turning the disk can be 100 carried out in any desired manner such as by the arrangement illustrated.

The disk rotating means shown in Figs. 2, 3 and 5 consists in stamping or otherwise forming a substantially rectangular tongue 105 10 in approximately the center of each of the disks 8. In other words each of said disks is provided with a U-shaped cut and the resultant tongue is bent on a line passing diametrically therethrough, which tongue is 110 substantially of a width equal to the diameter of the several openings 9. Thus by ex-

tending the tongues 10 through the openings 9, handles are formed for manipulating the disks.

In the form of the invention shown in Fig. 4, the portion 11 of the backing plate which has been cut out in forming the opening 9 is replaced and secured to the disk 8 and to a circular rotating plate 12 by a rivet 13. It will be noticed from this figure 10 that the plate 12 is considerably larger than the opening 9 so that when the rivet is in place removal of the disk 8 is prevented.

From the foregoing description taken in connection with the accompanying drawing, it will be seen that I have invented a very simply constructed calendar device which, because of the simplicity thereof and in view of the cheapness of the materials from which it may be formed, may be inexpensively manufactured. As a result such a device as this may find a ready market as a novel advertising display means. On the other hand if carefully made it will form a very attractive calendar which may be sold 25 at a considerable price.

I claim:

1. In a device of the class described, a face plate having a series of eight openings formed therein, the openings of said series 30 being alined, a plurality of circular disks

disposed behind the face plate, each having characters thereon to be registered with one of said openings, a backing plate having a series of openings, said last mentioned openings being disaligned, each being in registration with the center of one of said disks, a tongue struck from each of said disks extending through the adjacent opening in the backing plate for rotating the same, and a spacing strip between the two plates and having openings therein in which said disks are fitted.

2. In a device of the class described, a face plate having a series of eight openings formed therein, the openings of said series being alined, a plurality of disks disposed behind the face plate, each having characters thereon to be registered with one of said openings, a backing plate having a series of openings, said last mentioned openings being disaligned, each being in registration with the center of one of said disks, and a tongue struck from each of said disks extending through the adjacent opening in the backing plate for rotating the same.

In testimony that I claim the foregoing I have hereunto set my hand at Racine, in the county of Racine and State of Wisconsin.

ANNE VOETBERG.
